SHAG RAKE ATTACHMENT FOR VACUUM CLEANER NOZZLE

Edwin Fitzwater, Rahway, N.J., assignor to The General
Signal Corporation, New York, N.Y.

Filed Aug. 31, 1972, Ser. No. 285,213

Term of patent 14 years

Int. Cl. D15—05

U.S. Cl. D7—173

FIG. 1

FIG. 2

FIG. 3

FIG. 1 is a perspective view of the shag rake attachment for a vacuum cleaner nozzle, shown in the open condition.

FIG. 2 is another perspective view of the shag rake attachment, shown attached to a vacuum cleaner nozzle, which nozzle is shown in broken lines for illustrative purposes only and forms no part of the claimed design invention.

FIG. 3 is a bottom plan view of the shag rake attachment shown attached to a vacuum cleaner nozzle, as seen previously in FIG. 2.

I claim:
The ornamental design for shag rake attachment for vacuum cleaner nozzle, as shown and described.
